UNITED STATES PATENT OFFICE.

ONESIME FRECHETTE, OF ST. MALO, MANITOBA, CANADA.

DITCHING MACHINE.

Application filed May 31, 1922. Serial No. 564,759.

To all whom it may concern:

Be it known that I, ONESIME FRECHETTE, of the village of St. Malo, in the Province of Manitoba, Canada, have invented certain new and useful Improvements in Ditching Machines, of which the following is the specification.

The invention relates to improvements in ditching machines and an object of the invention is to provide a machine for cutting ditches at the side of a roadway, the machine being arranged so that it will make a cut along the side of the roadway, first in one direction and then in the other.

15 A further object of the invention is to provide a machine, the complete operation of which can be controlled by a single operator and which is arranged so that it is readily steered in any direction.

20 A further object of the invention is to provide a machine having an adjustable conveyor associated with the scoops and adapted to receive and discharge the dirt dug by one or other of the scoops, depending on the 25 direction of travel of the machine.

A further object of the invention is to provide an adjustable ejector associated with the discharging end of the conveyor which will receive the dirt discharged from 30 the conveyor and forcibly throw and distribute the same over the roadway.

A further object of the invention is to provide a flexible ditching machine which will accommodate irregularities in the road surface and whilst not interfering with the setting or operating of the scoops and the conveyor associated therewith.

40 A further object of the invention is to provide a ditching machine having a pair of opposed scoops delivering to a common conveyor and with the scoops supported so that they can be adjusted at the will of the attendant in respect to the ground on which they are operating.

45 With the above more important and minor objects in view, which will become more apparent as the description proceeds, the invention consists essentially in the arrangement and construction of parts hereinafter 50 more particularly described and later pointed out in the appended claims, reference being had to the accompanying drawings in which:—

Fig. 1 is a plan view of the machine.

55 Fig. 2 is an end view thereof.

Fig. 3 is a side view of a portion of the machine.

Fig. 4 is an enlarged detailed vertical sectional view transversely through the machine, the section being taken at 4—4' Fig. 1. 60

Fig. 5 is an enlarged detailed vertical sectional view through the conveyor, the section being taken at 5—5' Fig. 4.

Fig. 6 is an enlarged detailed vertical sectional view through the conveyor at 6—6' 65 Fig. 4.

Fig. 7 is a horizontal sectional view at 7—7' Fig. 6.

Fig. 8 is an enlarged detailed vertical sectional view at 8—8' Fig. 2. 70

Fig. 9 is a horizontal sectional view at 9—9' Fig. 8.

Fig. 10 is an enlarged detailed vertical sectional view at 10—10' Fig. 2.

Fig. 11 is a horizontal sectional view at 11—11' Fig. 10.

Fig. 12 is an enlarged detailed side view of the worm and worm wheel utilized for adjusting the scoops.

Fig. 13 is a vertical sectional view at 13—13' Figure 4.

In the drawings like characters of reference indicate corresponding parts in the several figures.

The end frames 1 and 2 of the machine 85 are stationary and rigid. Said frames are identically constructed and each comprises a lower horizontally disposed beam 3, an upper horizontally disposed beam 4, a vertically disposed guide 5 connecting the beams 90 at the ditch side of the machine, a vertically disposed connecting beam 6 at the road side of the machine, reinforcing angle braces 7 and 8 and reinforcing intersecting braces 9 and 10, the various parts being rigidly attached one to the other by riveting through corner plates provided. The guide 5 is constructed from an opposed spaced pair of vertically extending channel irons 11 and 12 100 and pairs of spaced guide plates 13 and 14 attached to the flanges of the channel irons, the spaces between the plates forming vertically extending slots 15 which receive and guide the parts later described.

By observing Fig. 9 it will be seen that 105 the guides are really substantially rectangular open centered columns having opposed side slots in the sides thereof.

The ends of the end frames carry vertically disposed pivot spindles 16 and 17 which are 110

provided with outstanding swinging axles 16' and 17' on which I mount steering wheels 17^x and 16^x. Pairs of steering cranks 18 and 18' also extend from the spindles 5 and the pairs of cranks are connected by forward and rear connecting bars 18^x and 18^x. The end frames are connected together by a bottom frame 19 which comprises similar end sections formed from four beams having their outer ends permanently attached 10 as indicated at 20 to the end frames and their inner ends converging and permanently connected to a bearing block 21. The bearing blocks are spaced apart a predetermined distance (see Fig. 5) and they receive 15 pivotally the spindle ends 22' and 22^x of the reach 22, end pins 23 and 23' passing through the ends of the spindles to prevent the spreading of the bottom frame.

20 It will be observed that the reach is disposed towards the road side of the machine and that the arrangement is such that the end frames can turn in the vertical plane to accommodate fluctuation in the road surface.

Within the open centres of the guides 5 at the ditch side of the machine I locate combined guide and bearing spools 24 which are adapted to move upwardly and downwardly 30 within the guides and which are transversely bored to receive pivotally stub shafts 25 permanently secured to the ends of a main beam 26 passing between the end frames. This main beam 26 supports the scoops and the 35 ditch side of the conveyor as later described.

The lower beams 3 of the end frame each carry at the road side of the machine a guide block 27 and the guide blocks receive combined guide and bearing spools 28 which are 40 mounted so that they can rotate within the blocks or move bodily endwise within the same a predetermined distance. The spools 28 receive pivotally aligned stub shafts 29 and 29' permanently secured at the opposite 45 ends of a vertically disposed road side frame 30.

The roadside frame comprises end spans 31 and 32 and a central substantially rectangular span 33, such being more or less 50 in the form of a Howe truss and the lower frame members of the central span provide a bearing for a centrally positioned pivot pin 34 which supports an open centred carrier frame 35, the carrier frame being 55 formed from two similar suitably connected parts which span the central span 33 above mentioned.

The carrier frame is reinforced by upper and lower pairs of brace bars 36 and 37 extending between the carrier frame and the main beam 26 and attached pivotally to the main beam as indicated at 38.

To the main beam 26 I secure a beam 39 which has the body part thereof spaced from 60 and parallel to the main beam. The beam

39 and the main beam 26 permanently support a pair of similar scoops 40 and 41 disposed at the ditch side of the machine and having their inner ends spaced apart a predetermined distance and the bottoms thereof 70 oppositely inclining, the arrangement being such that the scoops will dig and deposit dirt in a conveyor later described which is interposed between the scoops, it being understood that only one scoop works at a 75 time, depending on the direction of travel of the machine. The cutting edges of the scoops are provided with shares 42 which can be removed from time to time and sharpened as occasion requires.

The ditch end of the inclined conveyor 43 is suitably supported from the main beam 26 and is braced from the scoops (see Figures 6 and 7) and the road side end of the conveyor is carried by a bale bar 44 supported by a winding chain 45 attached to a chain wheel 46, the chain wheel being permanently secured to a winding shaft 47 carried by suitable standards 48 and 49 mounted more or less centrally on top of the carrier frame 35. A worm wheel 50 is secured to the shaft 47 and is engaged by a worm 51, the worm being operated by intermeshed bevel pinions 52 and 53. An operating shaft 54 is connected through a universal joint indicated at 54' with the bevel pinion 53 and the shaft is provided also with a hand wheel 55. The conveyor comprises similar side frames 56 and 57 suitably interconnected and the side frames of the conveyor support a series of suitably spaced small rollers 58 and a comparatively large end roller 59. A carrier belt 60 passes around the rollers and the belt is adapted to receive and discharge the dirt dug by the scoops. Suitable means 100 are provided for tightening the belt.

Here it will be observed that the bottoms of the scoops overhang the edges of the belt and are inclined adjacent the belt to accommodate the same, it being understood that the lower ends of the scoops are parallel to the road. The side frames of the conveyor towards the road side end carry two spaced parallel transversely extending top beams 61 and 62 which are supported also from the main beam 26 and on the beams 61 and 62 I locate a platform 63 which carries an internal combustion engine 64 of any approved type. A driving belt 65 connects the engine drive shaft with a driving pulley 66 secured to a countershaft 67 which is supported in suitable bearings provided on the ends of the beams 61 and 62. The countershaft and the drive shaft 68 of the conveyor are provided with suitable chain wheels connected by a driving chain 69.

At the road side end of the conveyor I have located a dirt ejector 70 which is pivotally swung from the conveyor shaft by end arms 71 and 72. The ejector is in the form 130

of a drum provided with lengthwise extending suitably spaced pitching bars 73 and it is driven by a driving chain 74 directly from the conveyor shaft 68, the arrangement being such that in the operation of the conveyor the ejector works at comparatively high speed and pitches the dirt deposited by the conveyor well over on to the road. Provision is made for adjusting the ejector in respect to the end of the conveyor, such being by way of lifting bars 75 and 76 connected to the arms 71 and 72 and cranks 77 and 78 extending from a cross shaft 79 carried by the beams 61 and 62. A further crank 80 is attached to the shaft 79 and is connected by an adjusting line 81 to a lever 82 mounted on the platform, the lever being provided with the customary hand latch and detent, the detent operating over a quadrant 83. Angularly disposed brace bars 84 and 85 extend between the beams 61 and 62 and the main beam 26. The beam 39 and the beam 26 support the operator's platform 86 which is located immediately above the ditch end of the conveyor.

To the projecting ends of the stub shafts 25 of the main beam I attach straps 87 which are supported by winding chains 88 extending upwardly and attached to chain wheels 89 mounted on comparatively short shafts 89' carried in suitable bearings formed in the standards extending upwardly from the upper beams 4 of the end frames. A worm wheel 90 is also secured to each shaft 89' and the worm wheels in each instance are meshed with worms 91 which are directly under the control of controlling shafts 92 passing over towards the operating platform 86 and fitted with hand wheels 93. The end frames 1 and 2 of the machine carry vertically disposed steering posts 94 and 95 and to the lower end of each post I attach a crank 96 which is pivotally secured in each instance to the steering bar 18^x and 18^z. A worm wheel 97 is secured to the upper end of each steering post and is meshed in each instance with a worm 98, the worm being directly under the control of an operating shaft 98' passing over towards the operator's platform and provided at the platform with a hand wheel 98^x.

By observing Figure 1 it will be seen that there are five hand wheels conveniently grouped adjacent the operator's platform so that he can readily control the various operations of the machine from this point. The lever 82 is also within convenient range of the attendant.

Universal joints are provided adjoining the worms in all the operating shafts and the ends of the said shafts which are fitted with hand wheels are all supported by swinging arms 99 which permit the said shafts to fluctuate and accommodate the

various adjusted positions of the machine parts.

The machine can be moved in either direction along the roadway, cutting first in one direction and then the other and can be steered as desired by manipulating the hand wheels 98^x. It is intended that the machine be pulled by a tractor operating on the roadway.

The attendant adjusts the scoops to the cut by manipulating the hand wheels 93 which controls the position of the main beam 26 carrying the scoops. He can also adjust the road side end of the conveyor up and down by manipulating the hand wheel 55 and the ejector is controlled through the adjustment of the lever 82.

I wish particularly to point out that the machine as a whole is particularly flexible to allow it to adjust itself to any irregularities in the road surface, and whilst permitting the attendant to set the scoops as he wishes.

Either end of the beam 26 can be adjusted independently of the other as provided for in the special bearings which operate in the guides. Further, any rocking action of the end frames is provided for in the pivoting arrangement of the reach. The roadside frame can also swivel in respect to the end frames and can adjust itself by a sliding movement of the spools 28 to accommodates any adjustment made in the main beam. The roadside end of the conveyor, being adjustably supported and suspended by the chain from the carrier frame, is not molested by any swinging movement of the roadside frame as the road side is free to swing around the pivot shaft 34. The arrangement provided allows the shafts 25, 29 and 29' to pull out of the bearings, carrying them a limited amount to accommodate the adjustment made in the machine.

It is believed that the above short description of the various adjustments provided will be sufficient to give a clear understanding of the flexibility of the machine which permits it to operate with success on all road surfaces which it may encounter.

A further feature of the machine is that it is entirely controlled by a single attendant.

What I claim as my invention is:

1. In a ditching machine, end frames presenting opposing vertically disposed guides at the ditch side of the machine, a main beam having the ends thereof mounted in the guides and independently vertically adjustable therein, a conveyor passing centrally transversely of the machine and having the ditch end thereof supported by the beam and the road side end adjustably supported and a pair of oppositely disposed up-

4
wardly converging scoops located at opposite sides of the ditch end of the conveyor and adjustable therewith and having their upper ends overhanging the conveyor and adapted to deliver earth on to the conveyor depending on the direction of movement of the machine along the ditch.

2. In a ditching machine, end frames provided at the ditch side of the machine and having opposing vertically disposed guides, steering wheels supporting the end frames, a main beam passing parallel with the ditch and having the ends thereof terminating in aligned stub shafts, combined guide and bearing spools slidably received within the guides and pivotally carrying the stub shafts, means for independently adjusting the stub shafts upwardly and downwardly within the guides, a transversely extending conveyor positioned centrally of the machine and having one end extending underneath and supported by the main beam and a pair of oppositely disposed spaced scoops located at opposite sides of the conveyor and supported by the main beam.

3. In a ditching machine, similar end frames, steering wheels supporting the end frames, an under frame connecting the end frames, a main beam located at the ditch side of the machine and passing parallel with the ditch and having the ends thereof independently and adjustably supported from the end frames, an upstanding road side frame carried by the end frames, a carrier frame spanning the road side frame and pivotally connected thereto centrally at the bottom, brace bars connecting the carrier frame with the main beam, said brace bars being pivotally connected to the beam and permanently attached to the carrier frame, a bale bar adjustably supported from the carrier frame, a transversely extending conveyor having the road side end supported by the bale bar and the ditch end supported from the main beam and underlying the same, a platform located above and carried by the sides of the conveyor, an internal combustion engine mounted on the platform, driving connections between the engine and the road side end of the conveyor and a pair of oppositely disposed scoops located at the ditch end of the conveyor and delivering the earth onto the same, depending on the direction of travel of the machine.

4. In a ditching machine, similar end frames, steering wheels supporting the end frames, an under frame connecting the end frames, a main beam located at the ditch side of the machine and passing parallel with the ditch and having the ends thereof independently and adjustably supported from the end frames, an upstanding road side frame carried by the end frames, a carrier frame spanning the road side frame and pivotally connected thereto centrally at the bottom, brace bars connecting the carrier frame with the main beam, said brace bars being pivotally connected to the beam and permanently attached to the carrier frame, a bale bar adjustably supported from the carrier frame, a transversely extending conveyor having the road side end supported by the bale bar and the ditch end supported from the main beam and underlying the same, a platform located above and carried by the sides of the conveyor, an internal combustion engine mounted on the platform, driving connections between the engine and the road side end of the conveyor and a pair of oppositely disposed scoops located at the ditch end of the conveyor and delivering the earth onto the same, depending on the direction of travel of the machine.

5. In a ditching machine, similar end frames, steering wheels supporting the end frames, an under frame connecting the end frames, a main beam located at the ditch side of the machine and passing parallel with the ditch and having the ends thereof independently and adjustably supported from the end frames, an upstanding road side frame carried by the end frames, a carrier frame spanning the road side frame and pivotally connected thereto centrally at the bottom, brace bars connecting the carrier frame with the main beam, said brace bars being pivotally connected to the beam and permanently attached to the carrier frame, a bale bar adjustably supported from the carrier frame, a transversely extending conveyor having the road side end supported by the bale bar and the ditch end supported from the main beam and underlying the same, a platform located above and carried by the sides of the conveyor, an internal combustion engine mounted on the platform, driving connections between the engine and the road side end of the conveyor and a pair of oppositely disposed scoops located at the ditch end of the conveyor and delivering the earth onto the same, depending on the direction of travel of the machine.

Signed at Winnipeg, this 10th day of January, 1922.

ONESIME FRECHETTE.
